UNITED STATES PATENT OFFICE

155,990

DESIGN FOR A COAT

Joseph Frumkes, Harrison, N. Y.

Application June 17, 1949, Serial No. 3,346

Term of patent 3½ years

(Cl. D3—4)

To all whom it may concern:

Be it known that I, Joseph Frumkes, a citizen of the United States, a resident of Harrison, New York, have invented a new, original, and ornamental Design for a Coat, of which the following is a specification, reference being had to the accompanying drawing, forming a part thereof.

Fig. 1 is a front view of a coat, showing my new design, and Fig. 2 is a rear view thereof.

I claim:

The ornamental design for a coat, as shown.
JOSEPH FRUMKES.
